PISTON

Irving E. Aske, Muskegon, Mich.

Original application December 11, 1942, Serial
No. 468,623. Divided and this application
October 9, 1943, Serial No. 505,599

10 Claims. (CL 309—9)

This invention relates to improvements in pistons.

This application is a division of my copending application Serial No. 468,623, filed December 11, 1942, for Piston and method of making the same.

The main objects of this invention are:

First, to provide an internal combustion engine piston having a large transfer of heat from the combustion surface of the piston to the ring belt section of the same and thence to the cooled cylinder walls, and also through the head of the piston to the inner side of the same where the heat is carried off by crankcase oil and greases, to thereby prevent overheating of said combustion surface and the consequent detonation of hydrocarbons over the piston and excessive use of lubricating oils.

Second, to provide an internal combustion engine piston of a laminated structure in which the thermal conductivity of the metal adjacent the combustion chamber is relatively great compared to that of the metal beneath, and in which the bonding contact between the adjacent surfaces of said metals is of a nature, first to insure a maximum transfer of heat from one metal to the other, and second to insure against separation of said metals when subject to the stress of high reciprocating speeds and long continued use.

Third, to provide a piston having a laminated structure of the character above described which can be made at a relatively low cost in large quantities, and of uniform quality as to homogeneity of bond, uniform thickness, and purity of metal top to insure a strong bond between the metals and a maximum transfer of heat.

Further objects pertaining to details and economies will definitely appear from the description to follow. The invention is defined in the claims.

In the accompanying drawing I illustrate my improved piston and a part of the apparatus and certain steps in the method of producing the piston.

Fig. 1 is a side view of one embodiment of the piston with parts broken away to show the head of the piston in central vertical section.

Fig. 2 is a detail view in central vertical section illustrating another embodiment of the piston.

Fig. 3 is a side view of a piston as cast, with parts broken away and illustrating the piston before a depression has been machined in the top thereof for the reception of a flux and copper granules.

Fig. 4 is a central vertical sectional view of the

head of the piston after one form of depression has been machined into the top thereof.

Fig. 5 is a central vertical sectional view of the head of the piston after a modified form of depression has been machined into the top thereof.

Fig. 6 is a fragmentary view, showing the machined piston of Fig. 4 relative to a heating element of an electric furnace.

Fig. 7 is a view similar to Fig. 4 after the depression of the piston is filled with a flux and copper granules.

Fig. 8 shows conventionally an electric furnace designed for operation at approximately the temperature indicated on the drawing.

Figs. 9, 10 and 11 each show conventionally electric furnaces or cooling chambers designed for operating at approximately the temperature indicated on the drawing.

Fig. 12 is a detail vertical sectional view of the embodiment of the piston shown in Fig. 7, showing the copper united to the piston body after the heating and cooling steps.

I will now describe the piston and the steps of the method of producing the same in reference to the accompanying drawing, in which the numeral 1 designates a piston casting having a head 2 and a skirt 3. The piston may be cast in the usual manner of foundry practice, the piston then appearing as in Fig. 3. In the embodiment of the invention shown in Figs. 1, 4, 7 and 12, I turn out the depression 5 in the head of the piston by means of a lathe centered at 4, leaving a pilot or central raised portion 6 about the center 4 and also leaving the peripheral ledge 7, preferably about one-eighth of an inch thick or other suitable thickness and height to retain molten copper in the depression. The machined surface of depression 5 is then cleaned, preferably by sand blasting, to remove the carbon-like smudge. Unless this film smudge is completely removed, the bonding between the copper and iron is not likely to be uniform nor closely knit to stand the stress of use in an engine, which involves various factors.

After thoroughly cleaning, the machined surface of depression 5 is thinly coated with a suitable flux, indicated at 8 in Fig. 7, a flux mixture of borax and manganese dioxide being suitable. Granules of pure copper 9A or copper bars are then placed in the depression 5, in such quantity as is calculated to fill said depression to the proper depth with molten copper, after the heating operation later described.

The piston 1 with flux 8 and copper 9A in the

depression 5 thereof is then placed on a carbon tray and inserted in an electric furnace 10, conventionally shown in Fig. 8 and operative at a temperature of 2050 degrees Fahr. or above the melting point of copper. At this temperature the copper is sufficiently fluid and the iron expanded to such a degree as to permit the fluid copper to enter the pores of the iron to a substantial depth.

Within a short period of time, five minutes are found to be a desirable period, after the copper is in a thoroughly fluid state such as would permit the same to flow over the surface of the depression, the piston 1 with the molten copper in the depression 5 is removed from the electric furnace 10 and is cooled in successive stages in the cooling chambers. The first cooling chamber 11, conventionally shown in Fig. 9, is maintained at a temperature of approximately 1600 degrees Fahr. The work is then placed in chamber 12, shown in Fig. 10, operating at a temperature of approximately 1000 degrees Fahr., and finally in chamber 13, shown in Fig. 12, operating at a temperature of approximately 130 degrees Fahr. An electric heating element 14 and its relation to a piston is shown conventionally in Fig. 6.

The above described cooling stages are highly important for the best bonding contact between the copper and the iron, since they have the important function of maintaining integral connection between the body of the copper 9 above the iron and the copper in the pores of the body of the iron beneath, otherwise the rapid and unequal degrees of contraction of the iron and the copper would more or less break or weaken the connection. Said cooling stages also prevent the iron part of the piston from warping from shape and from becoming too hard and brittle.

As a further step highly important in improving the bonding contact between the copper and the iron and also the purity of the metals, and thereby increasing strength and heat transference, the heating operation in the electric furnace 10 and the first two cooling stages in chambers 11 and 12 are in an atmosphere free of oxygen or other gas that might detrimentally oxidize or affect said metals. Such an atmosphere may preferably be a deoxidizing one, as hydrogen. This gas not only prevents formation of oxides but also reduces to a pure metallic state any metallic oxides that may exist in said metals.

Finally after completion of the above described operations, the piston is turned to proper size, the retaining ledge 7 being cut away in this operation. Also the peripheral edge of the layer of copper 9 is chamfered at 15, as shown in Fig. 1.

In the embodiments of the invention shown in Figs. 1, 4, 7 and 12, the same lathe center 4 and pilot 6 used in machining the depression 5 in the head 2 of the piston may also be used in these final machining operations, including the cutting of the ring grooves 16.

In the embodiment of the invention shown in Figs. 2 and 5, the central raised portion 6 of the embodiment of Figs. 1, 4, 7 and 12 is omitted, the depression 17 being machined in the head of the piston to leave only the peripheral retaining ledge 18. In the completed piston, as shown in Fig. 2, the layer of copper 19 extends over the central portion of the head and completely covers the combustion surface of the piston. The embodiments of Figs. 2 and 5 and the manner of producing the same is otherwise similar to the embodiment of Figs. 1, 4, 7 and 12.

In the pistons produced by the above described method, the copper has permeated the pores of the iron to such an extent and depth as to be visible in the body of the iron, like splashes of copper paint. In Figs. 1, 2 and 12 the copper is shown at 20 as extending from the body of the copper into the body of the iron beneath. The filling up of the microscopic voids in the iron extending for a substantial distance from the body of the copper into the iron beneath greatly strengthens the bond between the metals and also facilitates heat transmission from the copper to the iron. In the foregoing description reference has been made to the body of the piston as being composed of iron, but other suitable material or ferrous alloy may be used instead, and also other suitable metal substituted for the copper.

The piston of my invention is highly efficient for the purpose intended, that of diffusing heat from the piston and preventing its overheating, and the copper layer is bonded to the iron body so that it not only is securely retained but provides an effective heat transfer bond.

Having thus described my invention, what I claim as new and desire to secure by Letters Patent is:

1. A piston for internal combustion engines comprising a head portion of cast iron extending across the top of the piston and a layer of copper on said body portion covering substantially the entire area thereof, said layer of copper having integral filament-like portions extending for a substantial distance into the pores of the cast iron head portion, providing a direct heat transfer from said copper layer through the integral filaments thereof into the pores of the iron of the head portion, and providing a fixed bonding connection of said layer of copper to said cast iron head portion.

2. A piston for internal combustion engines comprising a head portion of cast iron extending across the top of the piston and a layer of copper on said head portion covering substantially the entire area thereof, said layer of copper having integral portions thereof extending into the pores of the cast iron head portion and providing direct heat transfer contact between the layer of the copper and the cast iron head portion and providing a fixed bonding connection for said layer of copper to said cast iron head portion.

3. A piston for internal combustion engines comprising a head portion of iron extending across the top of the piston and a layer of copper on said head portion covering substantially the entire area thereof, said layer of copper having integral portions thereof extending into the pores of the iron of the head portion providing a direct heat transfer contact therebetween and providing a fixed bonding connection between said layer of copper and said iron head portion.

4. A piston for internal combustion engines comprising a head portion of ferrous metal extending across the top of the piston and a layer of copper on said head portion covering substantially the entire area thereof and extending to the periphery thereof, said copper layer having integral portions thereof extending for a substantial distance into the pores of the ferrous metal of the head portion providing a heat transfer bond contact and a fixed securing connection between the layer of copper and said head portion of ferrous metal.

5. A piston for internal combustion engines comprising a head portion of ferrous metal ex-

tending across the top of the piston and a layer of copper on said head portion covering substantially the entire area thereof, said copper layer having integral filament-like portions thereof extending for a substantial distance into the pores of the ferrous metal of the head portion providing a direct heat transfer from said layer of copper, through the integral filaments thereof into the pores of the ferrous metal of the head portion and providing a fixed bonding contact between said layer of copper and the ferrous metal of the head portion.

6. A piston for internal combustion engines comprising a head portion of iron extending across the top of the piston, said head portion having an integral central raised portion of relatively small diameter, a layer of copper surrounding said raised portion and covering substantially the entire area of said head portion, said layer of copper having integral filament-like portions thereof extending for a substantial distance into the pores of the iron of the head portion, providing a direct heat transfer from said copper layer, through the integral filaments thereof into the pores of the iron of the head portion, and providing a fixed bonding connection between said layer of copper and said iron head portion.

7. A piston for internal combustion engines comprising a head portion of ferrous metal extending across the top of the piston, said head portion having an integral central raised portion of relatively small diameter, a layer of non-ferrous metal surrounding said raised portion and covering substantially the entire area of said head portion, said non-ferrous metal having a thermal conductivity substantially greater than the ferrous metal, said layer of non-ferrous metal having integral filament-like portions extending for a substantial distance into the pores of the ferrous metal head portion providing for a direct heat transfer from said layer of non-ferrous metal, through the integral filaments thereof into the pores of the ferrous metal of the head portion, and providing for a fixed bonding connection between said layer and said head portion.

8. A piston for internal combustion engines comprising a continuous head portion of ferrous metal extending across the piston and of such thickness and rigidity as to resist the explosive forces in use, and a layer of copper of substantial thickness covering substantially the entire area of the top of the piston, the copper of said layer being cast welded directly to the ferrous metal covered thereby and having cast welded bonding engagement with the ferrous metal providing a direct heat transfer therebetween and providing a fixed bonding connection between the layer of copper and the ferrous metal contacted thereby.

9. A piston for internal combustion engines comprising a continuous head portion of ferrous metal extending across the piston and of such thickness and rigidity as to resist the explosive forces in use, and a layer of copper of substantial thickness in superimposed relation to said head and covering substantially the entire area thereof, the copper of said layer being cast welded to the ferrous metal of said head portion and having integral filaments thereof in interlocking engagement with the interspaces of the ferrous metal.

10. A piston for internal combustion engines comprising a continuous head portion of ferrous metal extending across the top of the piston and of such thickness and rigidity as to resist the explosive forces in use, and a layer of non-ferrous metal having a higher heat conductivity than the ferrous metal and a lower fusion point cast welded to said ferrous metal head portion and covering substantially the entire area thereof, said layer of non-ferrous metal being of substantial thickness and having integral portions thereof in interspatial engagement with the ferrous metal providing a direct heat transfer contact therebetween and providing a fixed bonding connection between said layer of non-ferrous metal and the irregularities of said ferrous metal.
